UNITED STATES PATENT OFFICE.

WILLIAM H. BARTEN, OF GORDON, NEBRASKA.

APPARATUS FOR MAKING CONCRETE BLOCKS.

1,166,312.

Specification of Letters Patent. Patented Dec. 28, 1915.

Application filed March 19, 1912. Serial No. 684,773.

To all whom it may concern:

Be it known that I, WILLIAM H. BARTEN, a citizen of the United States, and a resident of Gordon, in the county of Sheridan and State of Nebraska, have invented certain new and useful Improvements in Apparatus for Making Concrete Blocks, of which the following is a specification, reference being had to the accompanying drawings.

10 This invention relates to improvements in the process and apparatus of making concrete blocks.

One object of the invention is to provide an apparatus of this character in which the blocks may be formed from a very wet, slushy mixture, thus insuring the perfect slacking of the cement and forming when set, a dense, waterproof, artificial stone for architectural or other purposes.

20 Another object is to provide an improved construction of mold having a plurality of removable partitions, whereby blocks of different sizes and shapes may be formed, and having means whereby the finished blocks may be readily removed therefrom.

25 A further object is to provide means whereby the finished blocks may be employed for forming a large number of other blocks at one operation.

30 With these and other objects in view, the invention consists of certain novel features of construction, combination and arrangement of parts as will be more fully described and claimed, it being further understood that changes in the specific structure shown and described may be made within the scope of the claims, without departing from the spirit of the invention.

35 In the accompanying drawings forming a part of this specification and in which like numerals of reference indicate similar parts in the several views, Figure 1, is a perspective view of my improved mold in position for being filled. Fig. 2, is a central vertical longitudinal sectional view of the same. Fig. 3, is a vertical cross sectional view taken on the line 3, 3 of Fig. 2. Fig. 4, is a detail perspective view of one of the partitions of the mold shown in Fig. 1. Fig. 5, is a plan view of one of the block facing plates which form the bottom of the mold. Fig. 6, is a longitudinal section of the same. Fig. 7, is a detail perspective view of one of the frames for connecting the facing plates with the ejector bar. Fig. 8, is a central vertical longitudinal section of the mold in an in-

verted position showing the manner in which the finished blocks are ejected therefrom. Fig. 9, is a detail perspective view of one of the core blocks forming hollow blocks in the mold. Fig. 10, is a similar view of a hollow block formed by the mold. Fig. 11, is a similar view of a half-tile block formed by a mold.

40 In the embodiment of the invention, I provide a mold 1, comprising a frame of any suitable size and shape and constructed of any suitable material, said frame being here shown as of rectangular, oblong shape, and the same is preferably formed of cast or sheet metal. The feet 3, are connected together by handle bars 4, to which are loosely connected bail shaped handles 5.

45 On the lower edges of the sides 2 are pairs of inwardly projecting lugs 6, which provide supports for bottom spacing and supporting bars 7, which are removably secured to the lugs by screws as shown. On the lower edges of the ends are formed inwardly projecting guide lugs 8, the purpose 50 of which will be hereinafter described.

55 Adapted to be arranged in the mold are a series of removable partitions, whereby the mold may be divided into a plurality of compartments, so that more than one block 60 may be formed. The partitions may be constructed and secured in the mold in a number of different ways. In the principal figures of the drawing the mold is shown as constructed of sheet metal and when so con-

65 structed partitions 9, are provided. These partitions have on the upper ends of their side edges laterally projecting lugs 10, which are engaged with notches 11, formed in the upper edges of the sides of the mold. On 70 the lower ends of their side edges the partitions are provided with right angular apertured lugs 12, with which and with holes 13, in the adjacent parts of the sides of the mold are engaged fastening bolts 14, whereby the partitions are removably secured in 75 position in the mold.

80 The bottom of the mold is in the form of a series of facing plates 37 which form the faces or outer surfaces of the blocks and which are preferably reversible, having one side smooth and the other side provided with either a depressed or embossed design, which will form either a depressed or embossed design on the face of the block when 85 the plates are arranged with the design faces thereof uppermost in the mold. When

smooth faced blocks are desired the smooth sides of the plates are arranged uppermost in the mold. The plates 37 have on their edges around the smooth sides thereof a narrow rim or flange 38, which when this side of the plates are up will form rounded or beveled corners on the smooth faces of the blocks.

The bottom plates 37 are spaced a sufficient distance apart to receive the partitions of the mold between the same and are secured in this spaced relation to a block ejecting bar 39, by pairs of rectangular frames 40, which with the exception of the two end frames are fastened to the facing plates and ejecting bar 39, by bolts 41, arranged therethrough as shown; said bolts having their heads countersunk into the face plates. The end frames are bolted to the facing plates 37, and the ejecting bar 39, by separate bolts 42, said end frames being secured in this manner to prevent the bolts from interfering with the operator's hands when engaged with the ends of the ejecting bar for the purpose of ejecting the finished blocks from the mold as will be hereinafter more fully described.

The ends of the ejecting bar are recessed or shaped as shown at 43, to receive the thumbs and palms of the hands during the ejecting operation. The ends of the side bars of the frames 40, are extended to form lugs 44, which engage the edges of the ejecting bar as shown. The side bars of the end frames 40, are arranged to slide between the guide lugs 8, on the ends 2^a, when the facing plates are forced through the mold in the operation of ejecting the finished blocks, said lugs thus guiding the facing plates and preventing the same from binding against the sides of the mold. When the facing plates 37, are in position to receive the concrete for forming the blocks said plates rest on the supporting bars 7, which are secured to the lugs 6, on the lower edges of the sides of the mold. By providing bars 7, of greater or less width the plates 37, will be supported at a greater or less distance up in the mold, thereby forming blocks of greater or less thickness as desired.

In order to form hollow or recessed blocks as shown in Fig. 10, I provide cores 45, which are preferably in the form of wooden blocks and are adapted to be secured to the facing plates 37 by screws or similar fastening devices. The core blocks 45, may vary in size to form the recesses in the concrete blocks any desired size or said core blocks may be of sufficient length to extend entirely across the plates 37, and between the partitions or ends of the mold. When the core blocks extend clear across the entire length of the facing plates and mold spaces, half tile like blocks will be formed as shown in Fig. 11. When two of the blocks shown in

Fig. 11, are placed together a hollow drain tile is formed. It will thus be seen that a number of different sizes, shapes and designs of blocks may be readily produced with my improved mold.

In forming blocks with my improved mold the same is placed across the trough A in which the concrete is mixed with the feet 3, of the mold, engaging the upper edges of the sides of the mixing trough as shown in Fig. 1, of the drawings. When the mold is thus arranged, the facing plates 37, will rest on the supporting bars 7, which are secured to the lugs 6, as hereinbefore described, said plates 37, thus forming the bottom of the mold. When the mold is in this position the wet concrete mixture is shoveled from the trough into the spaces between the partitions of the mold. When the mold has been filled in this manner the concrete is packed down in the same, and scraped off smooth with the shovel. After being thus filled and scraped off, the mold is inverted on a suitable surface and the blocks forced or ejected therefrom. When ejecting the finished blocks the bail shaped handles 5, are swung upwardly and grasped by the operator's fingers, while the recessed or shaped ends 43, of the ejecting bar 39, are engaged by the thumbs and palms of the hands. When thus held pressure is applied to the ejecting bar by closing the hands. This pressure on the bar forces the facing plates downwardly and inwardly and thus pushes the blocks out of the mold. When the ejecting bar has been brought down so close to the bails 5, as to preclude further pressure thereon, the bails are released and the handle bars 4, are grasped by the fingers, thus permitting the thumbs and palms of the hands to exert more pressure on the ejecting bar to force the blocks entirely out of the mold. When the bails 5, are released they are prevented from falling inwardly by stop lugs 46, arranged on the inner sides of the feet 3, as shown. The upper faces of the blocks when thus formed will be smooth or will have thereon a design according to whichever side of the facing plates 37, was uppermost in the bottom of the mold.

From the foregoing description taken in connection with accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my said invention, what I claim as new and desire to secure by United States Letters Patent is:

1. A rectangular mold of the character described, comprising sides and ends, of feet

- projecting from the corners, handle bars connecting said feet and held parallel to said ends, a bail loosely held upon each handle bar, inwardly directed lugs being disposed in sets of two and secured to the lower edge of said sides, bottom supporting spacing bars secured to said lugs, guide lugs extending from said ends, a bottom comprising a reversible plate, an ejecting bar, rectangular frames secured to said ejecting bar and to said bottom plate and reciprocating between said spacing bars, the two end frames sliding between said guide lugs, the ends of said ejecting bar being recessed, said bottom plate arranged to normally lie upon said spacing bars, said bails being adapted to be swung toward the ends of said spacing bars, whereby an operator may simultaneously grasp said bails and ejecting bar ends, and stop lugs secured to said feet limiting the inward movement of said bails. 5
2. A rectangular mold of the character described, comprising sides and ends, said sides being provided with oppositely positioned notches formed in their upper edges, of partitions having laterally projecting lugs upon their upper ends for co-action with said notches and provided with angular apertured lugs at their lower ends registering with suitable openings within said sides, and bolts passing through said apertured lugs and openings to removably hold said partitions within said mold, as and in the manner set forth. 10
3. A rectangular mold of the character described comprising sides and ends, said sides being provided with oppositely positioned notches formed in their upper edges, of partitions having laterally projecting lugs upon their upper ends for co-action with said notches and provided with angular apertured lugs at their lower ends registering with suitable openings within said sides, and bolts passing through said apertured lugs and openings to removably hold said partitions within said mold, as and in the manner set forth. 15
4. In testimony whereof I affix my signature, 20
in presence of two witnesses.
